7237X William Bryant, Davidson, Tennessee.

Letters Patent.

The Schedule reported to in these Letters Patent, and making part of the same, containing a description in the name of the said William Bryant himself of his improvement in the mode of supplying houses with water.

To all whom these presents shall come.

Be it known that of William Bryant, of the County of Davidson and State of Tennessee have invented new & useful improvements in supplying a house or houses with water; and that the following is a full and exact description of my said improvement. — My improvement, consists in the application of a railway carriage, to the purpose of conveying water from a spring, or other reservoir, to a house, or houses, without the assistance of any person either to supply the vessel in which the water is conveyed, or to pass ~~or~~ to pass with the carriage.

The following described plan for the application of the principle of my invention, answers well where the descent is sufficient to cause the carriage to pass down the railway to the water by its own gravity. At the place from which the water is to be conveyed a suitable reservoir, is kept sufficiently filled with water. A single rail railway, of the kind that permits the carriage body to hang directly under the rail, passes from the place to which the water is to be conveyed to the reservoir, and is about one foot in diameter, with an angle that it's easier to climb & handle to turn it, is placed on suitable supports at the end of the railway next the house. The railway at the end is necessarily over the water, and so made it, & without descent, that the body of the carriage or water vessel will sink

Oct 25, 1832

into the water so as to fill. The carriage consists of two small wheels enclosed in a narrow frame, placed one before the other & about eight inches apart from center to center, and are kept on the rail by guides or flanges; the vessel in which the water is conveyed is the only body of the carriage, it may be of sheet iron or any other suitable material; it is suspended from the wheel frame in such a manner as to hang directly under the rail. The water vessel has a valve in the bottom, which rises when it sinks in the water, and permits it to fill, & shuts as it is drawn out & retains the water in the vessel. A cord as long as the railway is attached at one end of the carriage, & the other end to the drum. (The operation is as follows. The drum is let at liberty to turn, and the carriage passes to the reservoir a idfully, it is then drawn back by the rope winding around the drum as it is turned. When the inclination is not sufficient for the carriage to pass to the water by its own gravity, a cord twice as long as the railway is used; and passes around a fixed pulley at the reservoir and also the drum, & the carriage is drawn backwards & forwards by turning the crank. In applying the principle of my invention as before named, I do not confine myself to the use of any one particular plan of the carriage, or method of supplying it with water, or to one particular kind of railway; different kinds of carriages & railways, & different methods of supplying the carriage may be used for the same purpose,) nor do I claim as my invention the conveyance of water on a railway by engine either locomotive or stationary; but claim as my invention or discovery the principle of supplying a house or houses with water by means of railways and carriages and the application of a rail way and carriage to that purpose, while the same

conveying the water remains at the house to which
it is conveyed.
